UNITED STATES PATENT OFFICE.

JOHN S. WORTH AND CHARLES BRECHT, OF COATESVILLE, PENNSYLVANIA, ASSIGNEES
TO JOHN S. WORTH AND WILLIAM P. WORTH, OF COATESVILLE, PENNSYLVANIA.

CAR END.

1,251,316.

Specification of Letters Patent. Patented Dec. 25, 1917.

Application filed September 23, 1914. Serial No. 863,196.

To all whom it may concern:

Be it known that we, JOHN S. WORTH and CHARLES BRECHT, citizens of the United States, and residents of Coatesville, county 5 of Chester, State of Pennsylvania, have invented certain Improvements in Car Ends, of which the following is a specification.

Our invention relates to certain improvements in the metallic ends of freight cars, especially of the box type. The invention 10 can be applied either to wooden cars, as a reinforcement for the ordinary wooden ends, or it may be substituted for the wooden ends, or it may be used for the ends of cars made 15 entirely of metal.

One object of our invention is to make the ends of corrugated metal, the main corrugations being triangular in shape so as to act as braces, as well as to reinforce the 20 ends of the car.

A further object of the invention is to make the greater number of the corrugations comparatively short at the load line so as to increase the strength of the end at 25 this point.

A still further object of the invention is to make the end so that it forms diagonal braces to reinforce the car structure.

Another object of the invention is to combine the plates of the particular form shown 30 with a reinforcing transverse beam, which is formed by bending the edge of one of the plates, or it may be formed of a separate sheet bent into shape. This particular form 35 of the invention is described and claimed in an application for patent filed by us of even date herewith under Serial No. 863,195.

In the accompanying drawings:—

Figure 1, is an elevation of a car end, 40 illustrating our invention;

Fig. 2, is a side view;

Fig. 3, is a plan view;

Fig. 4, is a vertical sectional view on the line $a-a$, Fig. 1;

Fig. 5, is an enlarged sectional view, 45 showing the joint and the reinforcing transverse beam, the section being similar to that in Fig. 4;

Fig. 6, is a view, in elevation, of a modification of the invention;

Fig. 7, is a plan view of the car end illustrated in Fig. 6;

Fig. 8, is a sectional view on the line $b-b$, 50 Fig. 6;

Fig. 9, is a view of a modification, in 55 which a series of triangular plates forms the car end;

Fig. 10, is a sectional view on the line $c-c$, Fig. 9;

Fig. 11, is a view of a modification in 60 which the beam is vertically arranged;

Fig. 12, is a sectional view on the line $d-d$, Fig. 11;

Fig. 13, is a view of another modification 65 in which the central beam is omitted, a rectangular plate extending from top to bottom and from one side to the other, and

Fig. 14 is a sectional view through one of the joints of the construction shown in 70 Fig. 13.

In the construction of metallic ends of railway cars it is essential to make the ends of sufficient strength to withstand the end strains of the load within the car, and it is also essential that the plate shall act as 75 a brace for the car framing and this end plate should be made of as light material as possible, and to accomplish this the plates are corrugated so as to add materially to their strength. We have found that by making the corrugations comparatively short, particularly at the point where the strength is required, we can materially increase the stiffness of the plate without increasing the thickness, and, by dividing the plates into 80 triangular sections, the plates not only act as braces, but also have the advantage of a number of short corrugations.

Referring in the first instance to Figs. 1 to 5 inclusive, the metal end 1 of the car is 90 made in two sections 2 and 3 and located between these two sections is a transverse reinforcing beam or rib 4. In the present instance, this rib is midway between the floor and the top of the car, but it can be 95 located at different points, as desired.

Each section 2 and 3 is bent at each edge to form flanges 5 and 6, respectively, and the lower section is bent to form a base flange 7, while the upper edge of the upper section 3 is plain and is shaped to correspond 100 to the shape of the roof of the car.

The beam, in the present instance, is made as clearly illustrated in Fig. 5, by bending the edge of the lower plate 2 so as to form 105 the upper and lower portions 8 and 9 of the beam and the end portion 10 thereof. The portion 8 is flanged at 11 and the lower por-

tion of the upper section 3 extends down over this flange so as to shed the water and to prevent it from gaining access to the joint.

In order to reinforce this beam and to close the inner end, we provide a plate 12 and a line of rivets 13 secures the flange 11, the plate 3, and the plate 12 together, while a row of rivets 14 secures the lower section 2 to the plate 12. This beam is preferably tapered from each side toward the middle, being deeper at the middle where strength is required.

The lower section 2 of the end plate of the car has a triangular rib or corrugation 15. The upper portion of this triangular rib extends substantially the full width of the car and the diagonal members extend to a point at the center of the end plate near the bottom thereof. Within the triangular rib or corrugation is a series of ribs 16, five in the present instance, increasing in length from the base to the center of the end plate of the car, and at each lower corner of the section 2 are triangular ribs 17 inclosing two short diagonal ribs 18.

Thus it will be seen that the short ribs are at the lower portion of the car in order to resist the strain which is greatest at this point, and the long ribs are close to the reinforcing transverse beam 4. The triangular ribs 17 also act as corner stays for the car body and strengthen the body of the car in this particular.

In the present instance, the upper section 3 is similarly corrugated like the lower section, but this may be modified without departing from the essential features of the invention.

19 is the main triangular rib, which corresponds to the rib 15 of the plate of the section 2, and within this triangular rib is a series of transverse ribs 20. 21, 21 are the upper corner triangular ribs, within which are the short diagonal ribs 22 forming the end of the design clearly illustrated in Fig. 1. This end can be made of comparatively light material, yet it will withstand considerable pressure. The transverse beam 4 also acts as a reinforcement and this beam can be made much deeper than the ordinary corrugation, owing to the fact that it is formed at the edge of one of the plates. In some instances, the lower plate may be made heavier than the upper plate, if desired, but the thickness of the material will depend considerably upon the character of the car to which it is applied.

In Figs. 6, 7 and 8, we have illustrated modifications of the forms illustrated in Fig. 1, and the section 2^a has a series of triangular ribs 15^a and 16^a instead of the triangular rib 15 and the horizontal ribs 16, and a single triangular projection 18^a is located within the triangular rib 17^a, and this is carried out in the upper section 3^a of the end plate.

In this instance the transverse beam 4^a is formed partly by the section 2^a and partly by the section 3^a, as illustrated in Fig. 8. The upper section has a downturned flange which overlaps the upturned flange of the lower section, and the two flanges are secured together by a line of rivets, as shown.

In Figs. 9 and 10, we have illustrated a further modification, in which the end plate is made of six sections. The two central sections 2^b and 3^b each has a triangular outer rib and longitudinal ribs differing in length within the triangular rib, and the corner sections 23 and 24 have triangular ribs and diagonal ribs within the triangular ribs. The corner sections 23 are secured to the section 2^b by a line of rivets, as illustrated in the drawings, and the sections 24 are secured to the section 3^b by a line of rivets 25, while the two sections 3^b and 2^b are secured together by rivets 26 and the plates at the rivets may be flat, one overlapping the other, or may be in the form of beams, as illustrated in Fig. 10, depending upon the character of the car under construction and the use for which it is intended.

In Figs. 11 and 12 we have shown the plates arranged so that the central beam 4^c is vertical instead of horizontal and beams are also shown at the joints of the corner plates 23^c and 24^c with the main plates 2^c and 3^c, the vertical beam in this instance is deeper at the lower end than at the upper end.

In Fig. 13, we have shown a central rectangular corrugated plate 2^d attached at the edges to the triangular plates 23^b and 24^b, and the joints may be in the form of beams of any depth according to the type of car to which the invention is to be applied. The ribs of the central plate can be arranged horizontally as shown or vertically as desired and the different sections of any of the car ends shown can vary in thickness, depending upon the use for which the car is intended.

It will be seen from the above construction, that we are enabled to make a car end of corrugated sheet metal in two or more sections; the joints at the sections can be reinforced by ribs or beams of any depth desired; the major portion of the corrugations is comparatively short, thus adding materially to the strength of the plate, and furthermore, considerably reducing the cost of manufacture.

We claim:

1. A metallic end for a freight car having diagonal ribs extending from the top and bottom of the vertical center line through the end of the car toward the side of the car and terminating near the horizontal center line through the end of the car and having disconnected reinforcing ribs at each corner.
2. A metallic end for a freight car having

diagonal reinforcing ribs extending from the top and bottom of the car at the vertical center line of the end and terminating at the sides of the car, and also having triangular reinforcing ribs at each corner.

5. An end plate for a freight car made in two sections; a heavy transverse reinforcing rib at the junction of the two plates, each plate having triangular ribs at the center and at the sides; and reinforcing ribs within the triangular ribs.

10. 3. An end plate for a freight car made in two sections; a horizontal reinforcing beam projecting outwardly beyond the surface of the plate, each plate having three triangular reinforcing ribs, one of said triangular ribs being a central rib and the others being located at the sides of each plate so that when the two plates are secured together the outside triangular ribs will form triangular braces at the corners of the end plate.

15. 4. The combination of an end plate for a freight car made in two sections; a horizontal reinforcing beam projecting outwardly beyond the surface of the plate, each plate having three triangular reinforcing ribs, one of said triangular ribs being a central rib and the others being located at the sides of each plate so that when the two plates are secured together the outside triangular ribs will form triangular braces at the corners of the end plate.

20. 5. An end plate for a freight car having

a central triangular rib and two side triangular ribs; with a series of transverse ribs differing in length and located within the main triangular rib.

25. 6. The combination in an end plate for a railway car, of two sections, one section having a flanged rib formed on its upper edge, the other section having a portion overlapping the flange of said rib, said rib forming a beam extending from one side of the car to the other, each section having a central triangular rib extending from one edge of each section to the other edge; and triangular ribs at the corners acting as corner braces for the car.

30. In testimony whereof, we have signed our names to this specification, in the presence 40 of two subscribing witnesses.
